United States Patent Office

Des. 206,864
Patented Feb. 7, 1967

206,864

CIRCULAR BUILDING

Eliot F. Noyes, New Canaan, Conn., assignor to Mobil
Oil Corporation, a corporation of New York

Filed Mar. 21, 1966, Ser. No. 1,573

Term of patent 14 years

(Cl. D13—1)

The figure is a top perspective view of a new circular building showing my new design.

I claim:

The ornamental design for a circular building, as shown and described.
